CAR HEATER

Carl W. Darrah and Frank M. Hardiman, Lockport, N. Y., assignors to General Motors Corporation, Detroit, Mich., a corporation of Delaware

Application May 27, 1935, Serial No. 23,624

10 Claims. (Cl. 257—137)

This invention relates to heating apparatus and more particularly to distribution of heat from heaters in motor cars.

It is usual in the present form of motor car heaters to have some source of heated air adjacent the dash board of a car and a fan for propelling that heated air out at right angles to the dash into the car. These heaters are mounted at some distance above the floor of the car and as the heat tends to rise it leaves a cold area near the floor which makes it uncomfortable for the feet of the driver and passengers as they get practically no heat.

It is therefore an object of our invention to provide a heater distributing heat for the floor area.

It is a further object of our invention to provide means for regulating the percentages, of the total heat distributed, which are directed downwardly and outwardly as desired.

With these and other objects in view, which will become evident as the specification proceeds, our invention will be better understood from the following specification wherein there are described the embodiments of our invention, which are illustrated in the accompanying drawings, in which,

Fig. 1 is a side elevation of the forward portion of a motor car showing our heater in position, parts being shown in section.

Fig. 2 is a perspective view of the heater alone, parts being broken away.

Fig. 3 is a vertical longitudinal section through the heater taken on the line 3—3 of Fig. 4.

Fig. 4 is a vertical transverse section through the heater on line 4—4 of Fig. 3.

Fig. 5 is a sectional view taken on the line 5—5 of Fig. 3.

A motor car having a frame 2, supports at its forward end a motor 4, and a radiator 6 with its surrounding shell 8. The radiator has its upper radiator header 10 connected by the conventional hose connection 12 to the water circulating system in the top of the motor head. The lower radiator tank 14 is also connected to the water circulating system of the motor block by a conventional hose connection 16. Directly behind the motor is the dash panel 18 upon which the heater, designated generally at 20, is mounted, which heater comprises the substance of our invention. The inlet tube 22 of the heater is connected, by suitable piping 24, with the motor head to cause the hot water therefrom to circulate to the heater. The outlet pipe 26 of the heater is also connected by pipe 28 to the lower

radiator header to discharge the water, which has flown through the heater, back to the cold part of the circulating system. The heater 20 is formed of an outer casing 30, generally in the shape of a cylinder with two flattened sides. 5 The rear portion of this outer casing has a series of holes 32 surrounding the periphery which act as air inlets. Adjacent the rear end of the casing is secured an angular bracket member 34 to which are secured bolts 36, which pass through 10 the dash board 18, and a backing plate 38 to secure the heater on the dash by means of nuts 40. On the interior of the casing, and also carried by the same bolts, is an electric motor 42 which drives the propeller fan 44 for circulating 15 air therethrough. Secured within the casing, substantially between its two extremities, is the radiating or heating element 46 to which the inlet and outlet pipes 22 and 26 are connected. Immediately to the rear of the radiating element 20 46, and surrounding the propeller means 44, is a circular fan housing 48 which assists in directing the air through the radiating element. The casing extends at considerable distance ahead of the radiator element 46 to form compartment 70 25 and the lower flat surface 48 has a series of air directing louvers 50 and the lower portion of each of the side surfaces have louvers 51 cut therein to direct the air both downwardly and slightly to each side. Upon the front of the casing is 30 mounted a ring member 52 which is securely fastened thereto and which supports an ornamental ring 54 by suitable screws 56. Within the compartment 70 and extending from top to bottom are two side plates 72 which form a rectangular inner chamber with the top and bottom of the casing. The forward portions of these side plates are bent at right angles to lie parallel to the rear face of ring 52 and are secured thereto by suitable screws 74. The plates are then bent 35 parallel to the main portion to lie adjacent the casing side walls, as shown at 76, and portions of the two are pressed out to interlock, as at 78. The opening in the forward portion of the ornamental ring is substantially rectangular and two doors 58 are pivotally supported on the inturned angular ends 60 of two U-shaped metal rods 61 held in the rim so that they may be opened to various positions to control the flow of air from 40 the front of the heater. Within the lower part of the compartment, ahead of the radiating element 46 and just behind the ornamental ring 54, is rigidly supported a curved baffle member 62 45 extending between the side plates 72 and which 50 55

pivottally supports at its upper extremity an extension baffle 64, which may be set in any desired position to regulate the forward flow of air. The central portion of the extension baffle 64 adjacent its pivotal point has an integral forwardly extending lip 68 which projects toward the forward portion of the casing and may be used to regulate the position thereof. Openings 80 are provided in the lower portions of the side plates 72 to allow air to flow to the louvers 51.

The operation of the heater is as follows: Air is drawn in through the openings 32 in the rear of the casing by the fan member 44 through the fan housing 48 and through the heat radiating surfaces of the radiating element 46 into the forward chamber 70. The air coming through the lower portion of the radiator 46 strikes first the baffle 62 and is discharged either through the louvers 50 in the bottom of the compartment 20 or through the louvers 51 in the lower side portions thereof. The air going through the top portion of the radiator 46 goes through the top of the compartment 70 and out through the forward doors 58, the amount passing through the doors of course being conditional upon the amount the doors are opened. Considering that the doors 58 are wide open and the baffle in the position shown in the full lines in Fig. 3, approximately 50 per cent of the air will be directed 30 forwardly and 50 per cent downwardly. If the movable extension 64 is moved down to the dotted line position, shown at 64', 75 per cent of the air will be discharged forwardly and the remainder down, while if the extension 64 is moved to the dotted line position 64" approximately 75 per cent of the air will be discharged downwardly and only 25 per cent forwardly. Of course it will be evident if the forward doors are closed tightly all of the air will be discharged downwardly. With this type of structure air is discharged directly on the floor boards in the forward portion of the front compartment and therefore eliminates the cold spot occasioned by most heaters at this locality. Due to the side louvers 51 air is directed toward the driver's feet as well as directly down upon the feet of the passenger occupying the right-hand seat. In this way the air can be controlled so that the passengers are comfortable in cold weather by having any required amount directed toward their feet and also a given amount directed toward the upper portion of the body so that they will be comfortable.

Although we have here illustrated the device as being used with hot water heaters, it is evident that the same might be used with a hot air or steam heater to the same advantage therefore the invention should not be limited to the present showing. It might also be noted that without either the rigid or adjustable baffle, with openings in the lower portion of the casing and with the closure of the doors, a certain amount of heat would be directed downwardly. We have therefore devised heat distributing means within the heater casing for distributing the air to different parts of the automobile body to prevent cold spots, and thus give more comfortable riding.

70 We claim:

1. In a heater, a casing, a heating element supported within the casing, air propelling means supported within the casing to force air through the heating element, and openings in a plurality of the faces of the casing at right angles to each

other ahead of the heating element whereby air may be distributed in different directions therefrom.

2. In a heater, a casing, a heating element supported within the casing, air propelling means supported adjacent the heating element to force air therethrough, openings in a plurality of the faces of the casing at right angles to each other ahead of the heating element and means therein to direct the flow of air from different openings. 10

3. In a device of the class described, a confined flow of heated air in a casing, means to discharge the air from the casing in a plurality of different directions and means to regulate the percentage 15 of the whole flow that is directed in the different directions, said last named means including closure members and flow directing members supported within the casing.

4. In a heater, a casing, a source of heated air 20 under pressure within the casing, louvers in the lower face of the casing adjacent the front, an opening in the front of the casing allowing the air to be discharged horizontally, a baffle to direct a portion of the air downwardly through the 25 louvers in the lower face and pivoted doors to regulate the flow of air from the front of the casing.

5. In a heater, a casing, a source of heated air under pressure in the casing, a plurality of openings in different faces of the casing, a rigid baffle secured to the casing between the openings to direct air from one set of openings and an adjustable extension on the end of the rigid baffle whereby the baffling effect may be regulated. 30 35

6. In a heater, a casing, a source of heated air under pressure in the casing, an opening in the front face of the casing, pivoted doors to act as closure members for the opening, a series of louvers in the lower face of the casing adjacent 40 the front, a rigid baffle secured to the casing between the front and the louvers for directing the air downwardly through the latter, an adjustable extension pivotally mounted on the end of the rigid baffle whereby by moving it to different 45 positions more or less air is directed downwardly through the louvers and out through the doors.

7. In a device of the class described, a casing, a source of heated air under pressure therein, a plurality of openings in the different faces of the casing for air discharge and a plurality of adjustable means for regulating air flow, one being closure members for one of the openings and the other flow directing means within the casing 55 whereby the percentages of air flow from the different faces of the casing may be controlled.

8. In a heater having a casing, a radiating element and a forced draft means, an opening in the forward face of the casing for discharging 60 air, a plurality of pivoted doors for the opening to regulate the flow of air therefrom, and a series of louvers in the lower face of the casing adjacent the front whereby the position of the doors will dictate the amount of air passing from 65 the louvers.

9. In a heater having a casing, a radiating element and forced draft means, an opening in the forward face of the casing for discharging air, a plurality of pivoted doors for the opening, a series of louvers in the lower portion of the casing adjacent the doors, a rigid baffle secured to the casing and an adjustable extension on the baffle whereby the doors, rigid and adjustable baf- 70 75

fies regulate the amounts of air discharged outwardly and downwardly.

10. In a heater having a casing, a source of heated air under pressure in the casing, an opening in the front face of the casing, louvers in the lower and side faces of the casing adjacent the front and means carried by the casing to direct

and apportion the flow of air through the different passages whereby heated air may be discharged either forwardly, downwardly or to the sides.
